KNITTED NON-RUN FABRIC AND STOCKING

Frank Stevenson, West Lawn, Pa., assignor, by mesne assignments, to Howard Hosiery Mills, Inc., Sinking Spring, Pa., a corporation of Pennsylvania

Application February 19, 1949, Serial No. 77,374

16 Claims. (Cl. 66—178)

This invention relates to the manufacture of knitted non-run fabrics and articles made therefrom, such as hosiery, and more particularly concerns certain improvements in this art appertaining to the subject matter of my two U. S. Patents Nos. 1,891,117 and 1,897,917, issued respectively, on December 13, 1932, and February 14, 1933.

One object of my invention is to provide a novel knitted non-run fabric of the type utilized in the production of hosiery, or other articles of wearing apparel.

Another object is to provide such a non-run fabric having certain desirable quality and appearance characteristics not present in the similar prior art non-run fabrics.

Another object is to provide such a non-run fabric which embodies certain unique elongated lock loops.

A further object is to provide such a fabric in which said elongated lock loops are arranged so that both legs thereof extend coursewise along the rear of the fabric, from their needle wale of origin across the legs of the loops of at least one adjacent needle wale.

Another object is to provide such a non-run fabric comprising coursewise extending elongated lock loops arranged to span at least three or more successive needle wales in the same course.

An additional object is to provide such a non-run fabric comprising courses which include plain loops and elongated lock loops so arranged that both legs of each lock loop floatingly extend coursewise from their wale of origin across the legs of at least one adjacent plain loop.

It is also an object to provide such a non-run fabric comprising courses which include plain loops and elongated lock loops so arranged that both legs of each lock loop extend laterally from their needle wale of origin across the legs of a plain loop of at least one adjacent needle wale and the bight portion of each lock loop is joined with the next lock loop of the course, by a plain needle loop of the succeeding course, at the needle wale of origin of said next lock loop.

Another object is to provide such a non-run fabric comprising one or more plain loop courses arranged in intermediate relation with courses provided with plain loops and elongated lock loops, the lock loops being overlappingly joined in each course and arranged in staggered relation throughout the fabric in such manner that both legs of each lock loop floatingly extend coursewise from their needle wale of origin across the legs of at least one adjacent plain loop.

Another feature of the invention resides in the production of the indicated non-run fabric improvements, by a new knitting method.

With these and other objects in view, which will become more readily apparent from the following detailed description of my improvements illustrated in the accompanying drawings, the invention comprises the novel non-run fabrics and method of producing the same, as more particularly defined by the hereto appended claims.

In the drawings:

2

Figure 1 is an enlarged rear view of a section of a novel non-run hosiery fabric made in accordance with my invention, and shows one arrangement of the unique elongated lock loops or stitches thereof.

Fig. 2 is a view similar to Fig. 1, but of a modified form of non-run hosiery fabric made in accordance with my invention.

Figs. 3 and 4 are similar enlarged perspective views of the non-run hosiery fabric shown in Fig. 1, and illustrate certain knitting elements used in the production thereof, in the positions that they occupy when carrying out my new knitting process.

Figs. 5 and 6 are similar enlarged perspective views of the non-run hosiery fabric shown in Fig. 2, and illustrate certain knitting elements used in the production thereof, in the positions that they occupy when carrying out my new knitting process.

Fig. 7 is a side elevational view of a knitted full-fashioned non-run stocking made in accordance with my invention.

Various knitted non-run fabrics have heretofore been produced which are suitable for the manufacture of hosiery, such as ladies' full-fashioned stockings, or other articles of wearing apparel. The production of such non-run fabrics on straight or full-fashioned knitting machines is well understood and involves the use of various knitting elements and mechanisms, all in accordance with the practice disclosed by the numerous prior art patents relating to this art.

The non-run fabric of my invention, can also be produced by utilizing such prior art knitting machine equipment and following the novel procedure taught by the description hereinafter set forth. One form of prior art knitting machine equipment which is suitable for practicing my present improvements, is disclosed in my said two Patents Nos. 1,891,117 and 1,897,917. These and other prior art patents, may consequently be referred to for further information concerning the details of the old and well-known means and method steps here involved, in conjunction with the novel phases of the invention.

Referring to the drawings, and first more particularly to Figs. 1, 3 and 4, it will be noted that the sections of my novel knitted non-run fabric there shown, comprise lock stitch courses generally designated by the letter L, and plain stitch courses generally designated by the letter P, formed of a yarn Y.

Each of the plain stitch courses P are produced in usual manner by conventional stitch-forming elements of a straight or full-fashioned knitting machine, including standard spring-beard knitting needles indicated by the reference numeral 1. The successively interconnected stitches 2 formed by the needles 1, are commonly referred to as the "needle wales" of the fabric, and the successively interconnected stitches 3 formed between the needle stitches or loops 2, are produced by the usual sinkers and dividers of the machine, and are commonly referred to as "sinker wales."

The lock stitch courses L comprise plain needle stitches or loops 2, arranged in intermediate relation with special elongated lock stitches or loops 4 that are produced by shifting points 5, in accordance with a procedure herein-after described.

The lock stitches 4 are arranged in staggered relation throughout the fabric, i. e., in the successive lock stitch courses L, the lock stitches 4 are positioned so that they extend coursewise across, or span, three needle wales in one lock stitch course, and are positioned one needle distance to the right, or left, in the next succeeding lock stitch course, so that the needle wales of the plain loop courses U, intermediate the lock stitch courses L, will each be in alignment with one or the other of the con-

nected ends of an elongated lock stitch 4, of one or the other of two succeeding lock stitch courses. This staggered arrangement of the lock stitches or loops 4, is provided to prevent so-called "runners" from traveling down the fabric, beyond the lock stitches or loops 4, when rupture of the yarn occurs in one of the plain needle loops 2 of any of the needle wales. The staggered arrangement of the lock stitches 4, throughout the fabric, as shown, follows the usual practice carried out in the production of non-run fabrics. However, to my knowledge, the elongated lock stitch 4, and its positional arrangement in the lock stitch course L, is new and is consequently to be considered as forming part of my invention.

In the non-run fabric shown in Figs. 1, 3 and 4, each lock loop 4, extends laterally from its needle wale of origin, to the left and both legs of the lock loop 4 floatingly cross the legs of a plain needle loop 2 of the next adjacent needle wale, at the rear of the fabric. The bight portion 4^a of each lock loop 4 is joined with the next lock loop of the course, by the lower portion of a plain needle loop 2, of the succeeding plain loop course P knitted, at the needle wale of origin of said next lock loop.

The non-run fabric shown in Figs. 2, 5 and 6, differs from that shown in Figs. 1, 3 and 4, in that each lock loop 4 is longer and in that two plain needle loops 2 are formed between the lock loops 4, so that both legs of the latter cross the legs of two plain needle loops 2, at the rear of the fabric, in each instance.

The lock stitches 4, provided in the fabric sections of Figs. 1, 3 and 4, are produced by utilizing the standard grooved shifting points generally indicated by the numeral 5, during the fabric knitting process. The shifting points 5 comprise a body 9 and a shank 10. One side wall and the back wall of the body 9, for the greater portion of the body of the shifting point 5 are cut away down to the shifting point extremity 12. The body of the shifting point also has a groove 10^a extending from 13 to 14, and this groove is varied in accordance with the knitting machine with which the shifting points cooperate. The construction of the shifting points 5, and their manner of use in producing a different lock stitch formation than that here involved, comprises the subject matter of my said two patents Nos. 1,891,117 and 1,897,917.

The different procedure followed in utilizing the shifting points 5, to produce the lock stitches 4 of Figs. 1, 3 and 4, so as to effect the formation of the lock stitch courses L, will become clear by referring to the upper portions of Figs. 3 and 4. As shown in Fig. 3, the needles 1, complete the knitting of three plain courses in usual manner. The shifting point bar of the machine which carries the shifting points 5 is then lowered vertically, so as to bring points 5 into cooperation with the knitting needles 1, in such manner that the tip or extremity 12, of each shifting point 5 will enter the usual groove (not shown) of the needle, while the upper end of the beard 15 of the needle 1 moves into the upper grooved portion 9 of the shifting point 5, thereby closing the beard. The needles 1 and points 5 are then moved down together, but the point bar is moved at a slower rate than the needle bar, so that the beards of the needles 1 will spring open and the tips of the needle beards will pass on the outside of the loops 2 and the tips of the points 5 will slide under the loops. The descending movements of the needle and point bars is then continued in unison until the loops (which are held stationary on the needles) are engaged higher on the points 5 and farther under the beards of the needles. The needle bar is then moved backwards so that the needles 1 move away from the points 5, and then both the needle and point bars are moved upwardly until the points 5 are above the knockover bits of the knitting machine. The needle bar is then brought to a standstill and the pointbar is moved laterally to the left until the points 5 have been moved a distance of two needles (Fig. 4). At the end of said lateral movement

of the points 5, the needle and point bars are moved down in unison until the upper ends of the needles 1 are just below the knockover bits of the machine and the grooves 10^a of the points 5 are also below the knockover bits in such position that the top ends of the needles fit into said grooves. The needle bar is then moved upwardly until the tops of the needles are above and inside the bight portion 4^a of the elongated loops 4, and the point bar is also moved upwardly at a much faster pace to their uppermost position, leaving the bight portions 4^a of the elongated loops 4 on the needles 1 under the sinkers of the machine. On the next downward movement of the needles the bight portions 4^a are then engaged under the beards of the needles. This operation is followed by the knitting of a plain loop course, as carried out in usual manner by the machine.

The normal knitting of a plain stitch course P, as usual, will cause each end of every elongated lock stitch 4, to be interconnected with the lower portion of a plain needle stitch 2, as clearly shown.

From the preceding description of operation of the shifting points 5, in producing the lock loops 4 of the fabric sections shown in Figs. 1, 3 and 4, and comparison of said figures with Figs. 2, 5 and 6 of the drawings, it will be clear that the lock loops 4 shown in the latter three figures are produced in substantially the same manner, i. e., by operating the shifting points 5 as already described, but moving them to the left an additional distance of one needle. Both legs of the lock stitches 4 will then extend across the two plain loops 2, formed between the needle wale of origin of the lock loops 4 and the needle wale where the bight portion 4^a of each lock loop 4 is joined with the lower portion of a plain loop 2 of the next succeeding plain loop course P knitted.

If desired, other shifting points may be utilized that have the left side wall cut away, as shown in my said Patent 1,897,817, instead of the right side wall as shown in the drawings hereof, and the mechanism for operating such different points can then be set to carry out the production of lock loops in the same manner as described, but to effect extension of the lock loops to the right.

It is also to be understood that the arrangement of plain knit courses P, between the lock loop courses L, may be varied as described. Instead of two plain knit courses, one such course may be provided, or more than two plain knit courses P may be provided.

When the non-run fabric is provided with lock loops which span four needle wales, as shown in Figs. 2, 5 and 6, runners developing in any particular plain loop needle wale will be stopped at one of three locking courses L, when the lock loops 4 thereof are arranged in the staggered relation shown in said Figs. 2, 5 and 6.

Fig. 7 shows a full-fashioned stocking of the type worn by girls or ladies. Such a stocking comprises a welt section W, a leg section L, and a foot section F. In accordance with the practice heretofore followed in producing non-run hosiery, such a stocking may be produced on a full-fashioned hosiery knitting machine so as to include the staggered lock stitch formation of my invention throughout the entire stocking fabric, by utilizing the means and following the method above described. If desired, only the welt section W, or some other section, or part of the stocking, may be so provided with the staggered lock stitch formation of my invention, or the latter may be similarly incorporated in knitted fabrics for producing other articles of wearing apparel.

It is to be particularly noted that the knitted non-run fabric of my invention has certain unique qualities and characteristics. For example, since the bight portion 4^a of each lock loop 4 is arranged in overlapping relation with the opposite end of the next adjacent lock loop, the formation of lace-like openings in the fabric is avoided and the front appearance of my novel non-run fabric very closely resembles that of a plain loop fabric. This feature is highly desirable and important, because

the lace-like appearance of non-run hosiery is usually considered to be objectionable from the standpoint of the users and purchasers of the finer grades of silk or nylon hosiery. Then too, the overlapping arrangement of the lock loops provides a stronger and more durable non-run fabric structure.

In the specification and claims the phrase "horizontal" is intended to refer to the coursewise extending legs 4 as shown in Fig. 1, which are elongated across or span a plurality of needle wales. These horizontally extending legs are also referred to as coursewise extending legs.

Of course, the improvements specifically shown and described, can be changed and modified in various ways without departing from the invention herein disclosed, the scope of which is more particularly indicated by the hereto appended claims.

I claim:

1. A knitted non-run fabric section, said fabric having laterally extending horizontal courses devoid of lock loops and also having between said courses devoid of lock loops laterally extending horizontal lock loop courses, with both legs of each lock loop floatingly extending coursewise across the legs of at least one adjacent plain loop, and comprising elongated lock loops both legs of each of which lock loops extend coursewise from their needle wale of origin horizontally across the legs of a loop of at least one adjacent needle wale.

2. A knitted non-run fabric section, said fabric having laterally extending horizontal courses devoid of lock loops and also having between said courses devoid of lock loops laterally extending horizontal lock loop courses, with both legs of each lock loop floatingly extending coursewise across the legs of at least one adjacent plain loop, and comprising elongated lock loops both legs of each of which lock loops extend coursewise along the rear of the fabric from their needle wale of origin horizontally across the legs of a loop of at least one adjacent needle wale.

3. A knitted non-run fabric section, said fabric having laterally extending horizontal courses devoid of lock loops and also having between said courses devoid of lock loops laterally extending horizontal lock loop courses, with both legs of each lock loop floatingly extending coursewise across the legs of at least one adjacent plain loop, and comprising elongated lock loops both legs of each of which lock loops extend coursewise from their needle wale of origin horizontally across the legs of the loops of two adjacent needle wales.

4. A knitted non-run fabric section comprising one or more plain loop courses arranged in intermediate relation with courses provided with elongated lock loops, the lock loops being arranged in staggered relation throughout the fabric section and each of said lock loops having both legs extending coursewise from their needle wale of origin across the legs of a loop of at least one adjacent needle wale, said lock loops being restricted to and all being located in and forming laterally extending horizontal lock loop courses and each lock loop course being separated from each other lock loop course by at least one horizontal plain loop course and both legs of each lock loop extending from its needle wale of origin horizontally across the legs of at least one plain loop of at least one adjacent needle wale.

5. A knitted non-run hosiery fabric section comprising one or more plain loop courses arranged in intermediate relation with courses provided with elongated lock loops, the lock loops being arranged in staggered relation throughout the fabric section and each of said lock loops having both legs floatingly extending coursewise from their needle wale of origin across the legs of a loop of at least one adjacent needle wale, said lock loops being restricted to and all being located in and forming laterally extending horizontal lock loop courses and each lock loop course being separated from each other lock loop course by at least one horizontal plain loop course and both legs of each lock loop extending from its needle wale of origin horizontally across the legs of at least one plain loop of at least one adjacent needle wale.

loop course and both legs of each lock loop extending from its needle wale of origin horizontally across the legs of at least one plain loop of at least one adjacent needle wale.

6. A knitted non-run hosiery fabric comprising one or more plain loop courses arranged in intermediate relation with courses provided with elongated lock loops, the lock loops being arranged in staggered relation throughout the fabric at the rear thereof and each of said lock loops having both legs floatingly extending coursewise from their needle wale of origin across the legs of a loop of at least one adjacent needle wale, said lock loops being restricted to and all being located in and forming laterally extending horizontal lock loop courses and each lock loop course being separated from each other lock loop course by at least one horizontal plain loop course and both legs of each lock loop extending from its needle wale of origin horizontally across the legs of at least one plain loop of at least one adjacent needle wale.

7. A knitted non-run fabric section comprising courses provided with plain loops and elongated lock loops so arranged that both legs of each lock loop floatingly extend coursewise from their wale of origin across the legs of at least one adjacent plain loop, said lock loops being restricted to and all being located in and forming laterally extending horizontal lock loop courses and each lock loop course being separated from each other lock loop course by at least one horizontal plain loop course and both legs of each lock loop extending from its needle wale of origin horizontally across the legs of at least one plain loop of at least one adjacent needle wale.

8. A knitted non-run fabric section comprising courses provided with plain loops and elongated lock loops so arranged that both legs of each lock loop extend laterally from their needle wale of origin across the legs of a plain loop of at least one adjacent needle wale and the bight portion of each lock loop is joined with the next lock loop by a plain needle loop of the succeeding course at the needle wale of origin of said next lock loop.

9. A knitted non-run fabric section comprising courses provided with plain loops and elongated lock loops so arranged that both legs of each lock loop extend laterally from their needle wale of origin across the legs of two adjacent needle wales and the bight portion of each lock loop is joined with the next lock loop by a plain needle loop of the succeeding course at the needle wale of origin of said next loop.

10. A stocking including a knitted non-run fabric section comprising elongated lock loops both legs of each of which lock loops extend coursewise from their needle wale of origin across the legs of a loop of at least one adjacent needle wale, said lock loops being restricted to and all being located in and forming laterally extending horizontal lock loop courses and each lock loop course being separated from each other lock loop course by at least one horizontal plain loop course and both legs of each lock loop extending from its needle wale of origin horizontally across the legs of at least one plain loop of at least one adjacent needle wale.

11. A stocking including a knitted non-run fabric section comprising coursewise extending elongated lock loops arranged to span at least three successive needle wales in the same course, said lock loops being restricted to and all being located in and forming laterally extending horizontal lock loop courses and each lock loop course being separated from each other lock loop course by at least one horizontal plain loop course and both legs of each lock loop extending from its needle wale of origin horizontally across the legs of at least one plain loop of at least one adjacent needle wale.

12. A stocking including a knitted non-run fabric section comprising one or more plain loop courses arranged in intermediate relation with courses provided with elongated lock loops, the lock loops being arranged

in staggered relation throughout the fabric section and each of said lock loops having both legs floatingly extending coursewise from their needle wale of origin across the legs of a loop of at least one adjacent needle wale, said lock loops being restricted to and all being located in and forming laterally extending horizontal lock loop courses and each lock loop course being separated from each other lock loop course by at least one horizontal plain loop course and both legs of each lock loop extending from its needle wale of origin horizontally across the legs of at least one plain loop of at least one adjacent needle wale.

13. A stocking including a knitted non-run fabric section comprising courses each provided with plain loops and elongated lock loops so arranged that both legs of each lock loop extend laterally from their needle wale of origin across the legs of at least one plain loop and the bight portion of each lock loop is joined with the next lock loop by a plain needle loop of the succeeding course at the needle wale of origin of said next lock loop. 15

14. A knitted non-run fabric construction, devoid of lace-like appearance, useful for hosiery and the like, formed of alternating plain loop courses and laterally elongated lock loop courses, both legs of each lock loop extending horizontally and laterally from its needle wale 25 of origin across the legs of at least one plain loop of at

least one adjacent needle wale and the bight portion of each lock loop being joined with the next lock loop of the course by a plain needle loop of the succeeding course at the needle wale of origin of said next lock loop.

5 15. The fabric construction of claim 14 in which the horizontally and laterally extending legs of the lock loops are positioned to the rear of and float upon the vertical legs of the adjacent loops in said lock loop course.

10 16. The fabric construction of claim 15 in which each lock loop course is formed of at least two plain loops for each locking loop.
